Primary Examiner — Kevin K Rudzinski*Assistant Examiner* — Amber J Rabie(74) Attorney, Agent, or Firm — Schwabe, Williamson & Wyatt, P.C.(57) CLAIM

I claim the ornamental design for a garment, as shown and described.

DESCRIPTION

FIG. 1 is a front perspective view of a garment, showing my new design;

FIG. 2 is a front view thereof;

FIG. 3 is a right side view thereof; and,

FIG. 4 is an enlarged view of the claimed region of FIGS. 1-3.

The dot-dash broken lines adjacent to the shaded area represent unclaimed boundaries of the claimed design. The remainder of the broken lines are provided for environmental purposes only and form no part of the claimed design.

1 Claim, 4 Drawing Sheets(56)
